CONSTRUCTION OF BILLIARDS

Richard Seifert, Vienna, Austria, assignor to
Metallbillard A. G., Chur, Switzerland, a Swiss
company

Application July 24, 1933, Serial No. 682,012
In Germany February 15, 1933

3 Claims. (Cl. 273—6)

My invention refers to improvements in the manufacture of billiards and pool-table and more particularly to the construction of the bed as well as the parts connected with the same.

5 Billiards and similar appliances usually comprise a wooden base-structure, a suitably reinforced frame supported by the former and a playing-plate or bed, for which slate, marble or similar substances are used and which is supported by a frame-structure. In some cases a wooden frame-structure duly reinforced in longitudinal and transverse direction is used for directly supporting the plate or bed. Base-structures made of a metal such as iron have also been suggested heretofore.

The cushion holders which, when made of wood, must be very voluminous, are usually connected with the plate or bed by means of screws.

Now on beds made of marble the rolling ball produces a hard sound and for this reason billiards have been usually equipped with a bed or playing-plate of slate. Slate, however, is a comparatively soft material of laminated structure and therefore very liable to become damaged, 25 which is particularly the case during transport. Nevertheless slate is generally preferred and chiefly employed in the construction of billiards beds or plates mainly because the connection of the same with the cushion or the abutting cushion frame by screws substantially contributes to a convenient repulsion of the balls free of resonance.

But just this connection by means of screws, which is possible only with the aid of nuts inserted into the slate is neither accurate nor lasting, as the inserted nuts become loose and the bores for the screw threads break away and become inaccurate in consequence of the parts concerned being repeatedly taken to pieces, when 35 the cloth is renewed or its proper tension is re-established.

The above-mentioned various drawbacks of the known complicated wooden or metallic billiard base-structures as well as of the fastening of the 45 playing-plate or bed are obviated according to the present invention thereby, that the playing-surface, plate or bed, upon which the game is executed, is made of metal, as for instance cast-iron, steel, light metal or a metal alloy and of course afterwards covered with cloth in the usual manner. The metal plate may be provided with reinforcing ribs and may consist of one piece or may be composed of a plurality of pieces.

50 The invention is illustrated diagrammatically and by way of example in the accompanying

drawing, on which Figure 1 is a bottom-view of the playing plate, Figure 2 is a vertical longitudinal section through the same, Figure 3 is a vertical section through the means connecting the plate, the cushions and the legs with one another, this figure being drawn in a greatly enlarged scale relatively to the other figures and Figure 4 is a bottom view of a modification, the playing plate being made in this case from two parts A and A¹.

5 The playing plate 1 consists of metal and is reinforced on its underside by means of ribs 7 (Figs. 1 and 2); 2 denotes a frame forming a support for cushioning means which is directly connected with the bed or plate 1 by screws 8 (Fig. 3) as well as with profiled wooden ledges or side rails 4 by screws 9. The rubber cushions 3 are inserted into the frame formed by said ledges, as shown in Fig. 3. The profile of the side rails 4 may be chosen as desired. On the bottom surface of the bed 1 are projections 5 (Figs. 1 and 3) to which the legs 6 are secured by means of screws 10. The legs may consist of any desired material. The playing plate may also consist of several parts.

10 The advantages presented by this construction, as well as by the use of metal for the playing plate and for the cushion frame are extraordinarily numerous.

15 Slate plates of such a quality and such a thickness as requisite for the purpose in view are obtainable only in very few countries, whereas there are nearly everywhere foundries and machine works, where metal plate suited for said purpose can be made.

20 Assembling the members constituting my present improved billiard is very simple and can be effected also by unskilled hands.

25 In the case of a large billiard it is possible to reduce the weight thereof considerably by using a light metal for the playing bed and by omitting all separate supporting members for said bed, which is rendered possible by the particular construction described; that lesser weight facilitates greatly the transport of the billiard.

30 Owing to the present particular construction 35 the billiard is practically safe against being damaged during the transport.

35 All sorts of repairs which might become necessary, such, for instance, as substituting a new cloth for the worn-off one, change of the rubber cushions, retensioning the cloth, and the like can be carried out far more easily and in a shorter time than is possible with billiards of any of the known constructions.

40 No other material than metal renders it pos- 55

sible to manufacture the playing plate so plane, accurate, properly right-angled, and lasting.

The metallic playing bed presents unforeseen advantages over all other materials up to now employed for said beds. There is no resonance whatever, the balls run noiselessly, and the very important Massé-strokes can be carried out in a surprisingly easy manner.

The metallic frame members have a low weight, 10 are more accurate, and join the playing bed properly right-angled; they allow of an ideal direct connection with the bed by means of screws.

As owing to metal contacting directly with metal the number of the screws can be smaller than heretofore and smaller screws can be used, 15 the assemblage of the members constituting the billiard is greatly facilitated and no inserted nuts are required. The dimensions of the metallic frame can be considerably smaller, whereby it is 20 rendered possible to reduce the breadth of the hand-support.

It is a matter of course that all types and kinds of billiards, pool tables a. s. f. can be designed according to this invention. I wish it to be understood that I do not limit myself to the particular 25 constructional form shown in the drawing merely

by way of example; various departures are possible especially in the details, without constituting, however, departures from the invention.

What I claim is:—

1. In a billiard table, a rectangular shaped playing plate of metal having a plane upper surface, a separate frame consisting of straight metal beams extending along the sides of the playing plate, means directly and rigidly connecting each of said metal beams independently to a side of 10 the playing plate and cushion carrying side rails fitting over and secured to said beams.

2. The device as claimed in claim 1, the playing plate having projections on its under surface supporting legs for said plate and means directly connecting said legs to said projections.

3. In a billiard table, a rectangular shaped playing plate of metal having a plain upper surface and consisting of several separate parts, a separate frame consisting of straight metal beams extending along the sides of the playing plate, means directly and rigidly connecting each of said metal beams independently to a side of the playing plate and cushion carrying side rails fitting over and secured to said beams.

RICHARD SEIFERT.
